UNITED STATES PATENT OFFICE.

JOHN EDWARD CARTMILL, OF ROSEVILLE, WEST VIRGINIA.

WRENCH.

1,078,901.

Specification of Letters Patent. Patented Nov. 18, 1913.

Application filed March 17, 1913. Serial No. 754,988.

To all whom it may concern:

Be it known that I, JOHN EDWARD CARTMILL, citizen of the United States, residing at Roseville, in the county of Fayette and State of West Virginia, have invented certain new and useful Improvements in Wrenches, of which the following is a specification, reference being had to the accompanying drawings.

This invention relates to new and useful improvements in wrenches, the object of the invention being to provide a wrench of the quick adjusted type wherein the shank of the wrench is provided with two opposed sets of rack teeth adapted to be engaged by pivoted pawls carried by the movable jaw to retain said jaw against sliding movement upon the shank in either direction.

Another object of the invention resides in the provision of new and novel means for mounting the pawls whereby a maximum of durability is obtained.

A further object of the invention is to provide a wrench of the above character of very simple construction embodying means for obtaining a very minute adjustment of the movable jaw.

A still further object of the invention is to provide a wrench which will possess advantages in points of efficiency and durability, is inexpensive to manufacture and at the same time is simple in construction and operation.

With the above and other objects in view, the invention consists in the novel features of construction and the combination and arrangement of parts to be hereinafter more fully described, pointed out in the claims and shown in the accompanying drawings, in which—

Figure 1 is a side elevation of a wrench constructed in accordance with my invention; Fig. 2 is a longitudinal sectional view taken through the movable jaw; Fig. 3 is a front elevation; Fig. 4 is a transverse sectional view through the shank, looking down upon the movable jaw; Fig. 5 is a longitudinal sectional view of the movable jaw, the actuating parts being removed; and Fig. 6 is a vertical sectional view through the movable jaw, taken on the line 6—6 of Fig. 5. Fig. 7 is a sectional view taken on the line 7—7 of Fig. 2.

Referring more particularly to the drawings, 1 indicates the shank which is provided at one end with a handle member 2 and

having formed at its other end a stationary jaw 3. One face of the shank is provided with the two opposed sets of teeth 4 and 5 respectively, the teeth 4 being somewhat larger in construction than the teeth 5. Slidably mounted upon the shank 1 is the movable jaw 6 which is provided with a cavity 7 in which are pivotally mounted the pawls 8 and 9, said pawls being adapted to alternately engage the teeth 4 upon the face of the shank 1 to hold said jaw in various adjusted positions. It will be apparent from the construction shown in the drawings that the pawls 8 and 9 are adapted to hold the jaw against backward movement upon the shank. In order to limit the outward sliding movement of the jaw, I provide a pivoted pawl 10 arranged within the cavity 7 and adapted to engage with the teeth 5, said pawl being normally held into engagement with the teeth by means of a coil spring 11 which is disposed between the pawl and one wall of the cavity.

The pawls 8 and 9 are normally held into engagement with the teeth 4 by means of the coil spring 12, one end of which is arranged within the recess 13 formed in the intermediate portion of the pawl 8. The other end of the spring 12 is arranged in the recess 14 formed in the projecting end 15 of the pawl 9, thus it will be apparent that the tension of the spring against the intermediate portion of the pawl 8 will normally hold the same into engagement with the teeth, said spring also pressing against the outer end of the pawl 9 to hold the inner end thereof into engagement with the teeth 4. The pawls 8 and 9 are so arranged that they will alternately engage the teeth 4 whereby a minute adjustment of the movable jaw will be obtained. It will be readily understood that while one of the pawls is engaged with the teeth 4, the other is disposed half way between the teeth so that a slight movement of the movable jaw upon the shank 1 will disengage the first pawl and engage the second pawl with the teeth, thus obtaining a minute adjustment.

Slidably mounted within suitable guides 16 is a plate 17 which is provided with a finger hold 18 projecting through an elongated opening 19 in the movable jaw and having its outer face corrugated, as shown at 20, so that the same may be quickly and readily manipulated. Formed upon the inner face of the plate 17 is a lug 21, which

is adapted to engage with the projecting pointed end 22 of the pawl 10 to disengage the same from the teeth 5, when so desired. Thus it will be apparent that upon the sliding movement of the plate 17, the pawl 10 will be disengaged from the teeth 5 to permit outward movement of the movable jaw. Slidably mounted within the front side of the cavity 7 is a second plate 23, having a finger hold 24 formed upon the outer face thereof and projecting through the opening 25, said finger hold being provided upon its outer face with suitable corrugations 26, whereby the same may be readily engaged by the thumb or finger to actuate the plate 23. The plate 23 is provided upon its inner face with a suitable recess 27 adapted to receive the projecting end 15 of the pawl 9 whereby upon the manipulation of the plate, 20 said pawl will be disengaged from the teeth 4. Upon the sliding movement of the plate 23, one end thereof will engage with the projecting lip 28 formed upon the outer end of the pawl 8 whereby the two pawls 8 and 25 9 will be simultaneously disengaged from the teeth to permit the movable jaw 6 to be moved forwardly upon the shank toward the jaw 3.

From the above description it will be 30 readily apparent that by the construction and arrangement of the pawls 8, 9 and 10 that the movable jaw 6 will be rigidly held in an adjusted position against the movement in either direction upon the shank. It 35 will also be apparent that the jaw 6 may be quickly and easily released for movement in either direction by actuating either of the plates 17 and 23.

It will be apparent from the above description taken in connection with the accompanying drawings, that I have provided a simple and durable wrench which is of very simple construction and embodying means for obtaining a very minute adjustment of the movable jaw. It is also apparent that the device is extremely simple in construction and can be manufactured at a comparatively low cost.

While I have shown and described the preferred form of my invention, it will be obvious that various changes in the details of construction and in the proportions may be resorted to for successfully carrying my invention into practice without sacrificing any 55 of the novel features or departing from the scope of the appended claims.

What I claim is:—

1. A wrench including a shank having a stationary jaw formed at one end, said shank having two sets of opposed teeth arranged upon one side thereof, said jaw being provided with a cavity, a pair of pivoted pawls arranged within said cavity and adapted to alternately engage one set of 60 teeth and a third pivoted pawl arranged

within the cavity and adapted to engage the other set of teeth whereby the movable jaw is securely held against movement in either direction and means for releasing said pawls to permit movement of the jaw 70 in either direction.

2. A wrench including a shank having a stationary jaw at one end, said shank having two sets of opposed teeth formed upon one face thereof, a movable jaw slidably upon 75 the shank and having a cavity formed therein, a pair of spring held pivoted pawls arranged in one side of the cavity and adapted to alternately engage one set of teeth, a third spring held pivoted pawl adapted to 80 normally engage the other set of teeth whereby the jaw is held against movement in either direction, and means for releasing said pawls.

3. A wrench including a shank having a stationary jaw at one end, said shank having two sets of opposed teeth formed upon one face thereof, a movable jaw slidably mounted upon said shank and having a cavity in one side thereof, a pair of pivoted 90 pawls arranged in one side of the casing and adapted to alternately engage one set of teeth, a coil spring having one of its ends engaging the intermediate portion of one of the pawls and its other end engaging with 95 the outer end of the other pawl, whereby said pawls will be normally held in engagement with the teeth, a third spring held pivoted pawl mounted in the cavity upon the opposite side thereof and adapted to normally engage the other set of teeth whereby the movable jaw will be held against movement in either direction, and means for releasing said pawls.

4. A wrench including a shank having a stationary jaw at one end, said shank being provided upon one face with two sets of opposed teeth, a movable jaw slidably mounted upon the shank and provided at one side with a cavity, a pair of spring held pawls 110 adapted to alternately engage one set of teeth, a third spring held pawl mounted in the cavity and adapted to engage the second set of teeth to hold said jaw against movement, and sliding plates mounted within said cavity and adapted to engage the outer ends of said pawls to release the same and permit the movable jaw to move in either direction.

5. A wrench including a shank having a stationary jaw at one end, said shank being provided upon one face with two sets of opposed teeth, a movable jaw slidably mounted upon the shank and having a cavity at one side thereof, spring held pivoted pawls 125 mounted within one side of the cavity and adapted to alternately engage one set of teeth, a third pawl arranged within the cavity and adapted to normally engage the second set of teeth, said pawls being provided 130

with outwardly projecting ends, sliding plates mounted within the cavity and adapted to engage said outwardly projecting ends to release the pawls from engagement with the teeth to permit the movable jaw to be moved in either direction, and finger holds formed upon said plates and adapted to project out through one side of the movable jaw

whereby the plates may be readily manipulated to release the pawls. 10

In testimony whereof I hereunto affix my signature in the presence of two witnesses.

JOHN EDWARD CARTMILL.
